THERMOSTATIC SWITCH

Ray J. D. Roberts and Alfred H. Faulkner, Chicago, Ill., assignors to Charles D. Hummel, Sr., New York, N. Y.

Application June 9, 1952, Serial No. 292,416

17 Claims. (Cl. 200—115.5)

1

Our invention relates to a thermostatic switch and more specifically to a switch of this type wherein a latch is utilized which requires manual resetting of the switch.

An object of this invention is to provide improvements in a thermostatic switch in which a temperature responsive latch is utilized to hold the switch in an operating position, and in which the switch parts move definitely, consistently and suddenly apart when a given thermal condition is reached as a result of an overload.

As another object of our invention, we have provided a thermostatic switch in which the thermostatic element and the circuit breaking parts are separate from one another, so that the break in the circuit effected by the switch does not occur in any part of the latch structure or at the thermostatic element, in which case the arcing due to breaking of the circuit would be detrimental to the consistent performance and operation of the latch and the thermostatic element, thereby to alter the thermal response of the element and the latching action.

Another object of the invention is the provision of a thermostatic switch in an electrical fitting such as a connector plug, by which electrical apparatus is connected to a conventional outlet or power source. If the electrical apparatus has no circuit breaker, it is advantageous to provide a circuit breaker therefor which is subject to being reset and which is connected in the line through which electrical power for the apparatus is obtained. In the disclosed structure, we have provided an advantageous arrangement of a thermostatic element and switch parts with respect to certain members of an otherwise conventional fitting, for example, the connecting prongs of an electrical plug.

Our invention comprehends as a further object an arrangement of a manually operable resetting member for a thermostatic switch in an electrical fitting which prevents the fitting from being utilized if the resetting member is positioned to prevent the switch from opening under an electrical overload. We have arranged the resetting member with respect to the prongs of an electrical plug so that when the resetting member is positioned to reset and hold the switch parts together, the prongs of the plug are prevented from entering a conventional prong-receiving fitting.

Other objects and advantages of the invention will be apparent from the following description and the accompanying drawings, in which similar characters of reference indicate similar parts throughout the several views.

2

Referring to the two sheets of drawings:

Fig. 1 is a perspective view of one embodiment of an electrical fitting in the form of a connector plug, in which the thermostatic switch of our invention is utilized;

Fig. 2 is a plan view of the electrical fitting and thermostatic switch of Fig. 1, one part of the casing for the electrical fitting being removed;

Fig. 3 is a transverse sectional view taken substantially on a line 3—3 of Fig. 2, and in the direction of the arrows;

Fig. 4 is a transverse sectional view taken substantially on a line 4—4 of Fig. 2, and in the direction of the arrows;

Fig. 5 is a longitudinal sectional view of our connector plug and thermostatic switch assembly, taken substantially on a line 5—5 of Fig. 2, as indicated by accompanying arrows;

Fig. 6 is a perspective view of a part of the illustrated structure;

Fig. 7 is a fragmentary plan sectional view of one end of the illustrated structure with the parts in one operating position;

Fig. 8 is a fragmentary plan view, similar to Fig. 2, but showing only one end of the structure and depicting different operating positions of certain parts;

Fig. 9 is a plan view, with parts in section, of a modified embodiment of our invention having one part of the casing removed and indicating a panel to which the embodiment is attached;

Fig. 10 is a fragmentary longitudinal sectional view taken substantially on the line 10—10 of Fig. 9, and in the direction of the arrows;

Fig. 11 is a transverse sectional view taken substantially on the line 11—11 of Fig. 9, and in the direction indicated by arrows; and

Fig. 12 is a fragmentary plan view, partly in section and similar to Fig. 9, but showing different operating positions of parts of the switch.

Having reference to the drawings, in which two exemplary embodiments of the invention are shown for illustrative purposes, the numeral 20 designates an insulating casing for one embodiment of a thermostatic circuit breaking device of our invention which takes the form of an electrical plug having two prongs 21 and 22 projecting from one end thereof and a connecting cord 23 extending from the other end and including two insulated conductors 24 and 25. The casing

20 comprises two mating parts, one of which may be termed a base 26, and the other a cover 27. Both the base 26 and the cover 27 are made, as by molding, of a suitable insulating material such as Bakelite, and are held together by a threaded sleeve 28 embedded in the base 26 and a screw

55

29 passing through the cover 27 and threaded into the sleeve 28. The casing parts 26 and 27 also form part of the modified embodiment of the invention, as illustrated in Figs. 9 to 12. Certain portions of the casing parts which function in the first embodiment of Figs. 1 to 8 do not function in the second embodiment and thus in some instances stand alone in Figs. 9 to 12 and are more easily seen there.

The prong 21 comprises a long contact portion 30 external to the casing 20, a long connecting portion 31 internal to the casing 20 and displaced laterally from the external portion 30, and short intermediate connecting portion 32 within the casing. The prong 22 has corresponding contact, connecting and intermediate portions 33, 34 and 35, respectively. The prongs are so disposed on the base 26 that the internal connecting portions 31 and 34 are spaced farther from one another than the external contact portions 30 and 33. The regions of the external portions 30 and 33 of the prongs adjacent the intermediate portions 32 and 35 rest in grooves 36 in an end wall 37 of the base 26; the intermediate portions abut the inner side of the end wall 37; and the inner ends of the internal connecting portions 31 and 34 extend into recesses 38 and 39 in raised regions 40 and 41 respectively of the base 26.

A fixed or stationary contact 42 is secured to the inner side of the internal connection portion 34 of the prong 22 near its inner end, and the region of the outer side of the connecting portion 39, directly opposite the contact 42, is backed by a boss 43 of a side wall 44 of the base 26. The side wall, including the boss 43, is below the raised region 41.

The stationary contact 42 is mounted in position for engagement by a movable contact 45, as depicted in Fig. 2. The contact 45 is secured to the free end of a spring arm 46 which is generally in the form of a U having one short leg 47 to which the contact 45 is secured and a long leg 48, the end of which constitutes a fixed end of the spring arm 46, because it is secured to the base 26 through a metal terminal 49 and screws 51. This terminal has a flange 49a to which the fixed end of the arm is joined by a rivet 50. Screws 51 are threaded into the raised region 41 of the base 26 for holding the metal terminal 49 in place on the base. An insulating strip 52 is clamped between the terminal 49 and the raised region 41 and extends in contact with one edge of the connecting portion 34 of the prong to a position somewhat beyond the stationary contact 42, to hold the end of the prong portion 34 in the groove 39. A screw 53 is threaded through the terminal 49 to secure an end of one of the conductors 24 and 25 to the terminal 49. A recess 54 (Fig. 4) in the raised region 41 of the base 26 provides space for the end portion of the screw 53 which is threaded through the terminal 49.

The other of the conductors 24 and 25 has an end connected by a screw 55 to a metal terminal 56 which is secured to the raised region 40 of the base 26 by screws 57, as shown in Figs. 2 and 4. An insulating strip 58 is clamped between the raised region 40 and the terminal 56 and extends in contact with the side of the end region of the internal prong connecting portion 31 to hold it in the groove 38. The raised region 40 has a recess similar to the recess 54 on the opposite side of the base, which provides space for the end portion of the screw 55 threaded through the terminal 56.

A heat-responsive or thermostatic element 75

which, in the disclosed structure, constitutes a bimetallic element 59, has a fixed or stationary end secured by fastening means, such as a rivet 60, to a flange 61 of the terminal 56. A latching projection 62 is secured to the free end of the thermostatic element 59. A flexible electrical lead wire or connecting element 63 is metallically bonded, as by soldering or welding, to the thermostatic element at or near its free end, and to the internal connecting portion 31 of the prong 21.

A latch cam 64, made of a suitable insulating material, is mounted for rotational movement on a spindle portion 65 of a metal stud insert 66 embedded in a raised region 67 of the base 26, as shown in Figs. 2 and 5. The latch cam is supported by a shoulder 66a (Fig. 5) on the insert at the end of the spindle portion 65 and also on a ridge 68 rising from the region 67 of the base 26. The latch cam 64 has a relatively pointed portion 69 disposed for engagement with the free end of the arm 46 to urge the movable contact 45 into engagement with the stationary contact 42. The cam also has a shoulder portion 70 engageable with the latching projection 62 on the thermostatic element. The portions 69 and 70 are joined by a smoothly curved surface 71 on the latch cam.

The latch cam 64 is moved to the position shown in Fig. 2 by a manually operable resetting member 72 which is separately shown in Fig. 6. This resetting member has oppositely extending spindle portions 73 and 74 by which it is supported for rotational movement in recesses 75 and 76 in the region 67 of the base 26 and a region 77 in the cover 27, respectively. The resetting member 72 has a handle or gripping end portion 78 provided with a serrated or ridged end 79 adapted for frictional engagement by a finger of an operator. It also has an operating portion 80 which is connected to the spindle portion 73 and to the handle or gripping end portion 78, and is adapted to engage a curved protrusion 81 on the latch cam 64 when resetting the latch as indicated in Fig. 8. The ridge 68 on the base 26 is in position to be engaged by the operating portion 80 of the resetting member, and acts as a stop for limiting movement of the resetting member in one direction beyond the position of Fig. 8, in which position the handle portion 78 extends from the end of the casing 20 generally in the direction of the prongs 21 and 22.

When the resetting member 72 is not in use, the handle portion 78 thereof extends transversely of the prongs and lies in flush relationship to the end of the casing 20 between the ends of the base 26 and the cover 27, as shown in Figs. 1 and 2. The serrated end 79 protrudes from the casing to provide for accessibility of the resetting member. The handle portion 78 has a raised projection 82 on one surface which is frictionally engageable with cover 27, as shown in Fig. 3, to prevent the resetting member from being readily swung by gravity from the position of Fig. 2 to that of Fig. 8 when the device is held so that the prongs 21 and 22 extend downwardly from the casing 20.

The cover 27 has a thick portion 83 (Fig. 5) which engages the end of the spindle portion 65 upon which the latch cam 64 is pivoted. There is small amount of clearance between the portion 83 and the latch cam 64 when the latch rests on the shoulder 66a. Thus the latch is retained on the spindle portion 65, but the thick portion 83 of the cover does not bind the latch. The thick

portion 83 also engages the internal portions 31 and 34 of the prongs 21 and 22 to help the insulating pieces 58 and 52 in keeping the prongs in place in the base 26. The cover has a side wall or flange 84 which engages the side wall 44 of the base 26 and the extension of such wall alongside the raised region 41, which extension takes the form of a shoulder surface 85 which is below the raised region 41, as shown in Fig. 4. The side wall or flange 84 of the cover engages the outer side surface of said raised region. As also depicted in Fig. 4, the cover has another side wall or flange 86 opposed to the side wall or flange 84 and which engages a shoulder surface 86 of the base 26. The side wall 86 on the cover also engages the outer side surface of the raised region 40 of the base.

The shoulder surface 88 has a curved recess 89 through which access is had to an adjusting screw 90 threaded in a hole 91 at the raised region 40 of the base 26. The inner end of the screw 90 engages the thermostatic element 59 and is adjusted thereagainst when the element is being calibrated. Once the screw 90 is properly adjusted the end of the outer end of the hole 91, at the recess 89, is sealed with suitable material to cover the outer end of the screw, as indicated at 92 in Fig. 4. The side wall 86 of the cover has a curved projection 93 which fits in the recess 89 and covers the sealed end of the hole 91 when the cover is in place on the base.

The base 26 and cover 27 have ends 94 and 95 which are recessed and grooved to provide between them an opening 96 adjoined by an internal groove 97. The opening and groove are adapted to receive a flexible collar or bushing of a suitable material such as rubber which has a flange (not shown) that extends into the groove 97 in the opening 95 and prevents dislodgement of the bushing from the opening and relieves strain on the terminal connections if the cord is pulled.

In the operation of the embodiment illustrated in Figs. 1 to 9, the connecting prongs of the plug may be inserted into a conventional outlet connector for electric power having contact elements for making contact with the prongs 21 and 22, and the electrical device which is to be protected by the invention may be connected to the conductors 24 and 25 in the cord 23. Alternately, the connector into which the prongs 21 and 22 are inserted may be mounted on or connected with the electrical machine, and the conductors 24 and 25 may be connected to the source of electrical power. At the start of operation the parts are positioned as shown in Fig. 2, with the latching projection 62 on the thermostatic element 59 engaging the shoulder portion 70 of the latch cam 64, in which position the pointed portion 69 of the latch engages the free end of the spring arm 46 and holds the movable contact 45 thereon in engagement with the stationary contact 42. Thus, current flows on one side through the prong 21, the flexible connector 63, the thermostatic element 59, the terminal 56, and one of the conductors 24 and 25 through the electrical device being protected; and current flows on the other side through the prong 22, the contacts 42 and 45, the spring arm 46, the terminal 49, and the other of the electrical conductors 24 and 25 through the device being protected. When an overload occurs, an excessive current flows through the thermostatic element 59, causing it to heat sufficiently that its free end and the projection 62 thereon move away from the shoulder portion 70 of the latch 64. When the projection 62 no longer engages the shoulder portion 70,

the latch cam 64 is no longer held against rotational movement on the spindle portion 65, and the spring arm 46, by virtue of its resilience and its attachment to the flange 49a of the terminal 49, shifts to the position of Fig. 7 and breaks the connection between the movable contact 45 and the stationary contact 42. This breaks the circuit between the source of power and the device being protected.

After the circuit is broken, the thermostatic element 59 cools, and the free end thereof moves back toward the latch cam 64. However, the projection 62 on the thermostatic element does not then engage the shoulder portion 70 on the latch cam 64, because the spring arm 46, in moving to the position of Fig. 7, has angularly shifted the latch cam until the curved surface 71 thereof is opposite the projection 62. Thus, to reset the switch, the latch cam 64 must be shifted angularly back to the position of Fig. 2, and this is accomplished by manual movement of the resetting member 72. The resetting member is angularly shifted from the position of Fig. 2 to that of Fig. 8, and in such movement, the operating portion thereof engages the protuberance 81 on the latch cam 64 to shift the latch cam back to its contact holding position, as shown in Fig. 8. The shoulder portion 70 of the latch cam is moved just beyond the projection 62 on the free end of the thermostatic element 59, so that when the resetting member 72 is returned to its normal out-of-the-way position of Fig. 2, the latch cam is held in the position of Fig. 2. Return of the latch cam to its original position shifts the free end of the spring arm 46 so that the movable contact 45 thereon reengages the stationary contact 42 on the prong 22. The circuit between the source of power and the electrical device being protected is thus reestablished.

It will be noted that the shoulder portion 70 and the pointed portion 69 of the latch cam 64 are approximately 90 degrees apart when considered with reference to the spindle portion 65 about which the latch cam swings. As a result, the spring arm 46 carrying the movable contact 45 can be approximately parallel to the thermostatic element 59 and the spindle portion 65 providing the axis of movement for the latch cam 64 can be generally in line with the spring arm 46. Because the thermostatic element 59 and the spring arm 46 are generally parallel, and the latch pivot 66 is generally aligned with the spring arm 46, the thermostatic element, the spring arm, and the latch cam can be conveniently arranged in a conventional fitting, such as the electrical plug shown, to provide a casing 20 which is approximately the same, or only slight greater than the width of a conventional plug connector without the thermostatic means of our invention.

If the resetting member 72 is kept in the resetting position illustrated in Fig. 8, it holds the latch cam 64 in the position shown in this figure, and thereby prevents the spring arm 46 from moving the movable contact 45 away from the stationary contact 42 regardless of the flexing of the thermostatic element 59 resulting from an overload. However, it is to be noted that in the resetting position the manipulating portion 73 of the resetting member extends out from the end of the casing 20 in the general direction of the exterior portions 30 and 33 of the prongs 21 and 22 so as to prevent the prongs from being inserted into a conventional outlet connector for electric power. Thus, with the embodiment of the invention described, the re-

setting member cannot be employed to defeat the purpose of the thermostatic element.

A second and modified embodiment of our invention is illustrated in Figs. 9 to 12. The same base 26 and cover 27 comprise the casing. Similarly, the spring arm 46 carries the movable contact 45 at its free end and is shaped generally in the form of a U having the short leg 47 to which the movable contact is secured and a long leg 48 having an end which provides the fixed end of the spring arm 46 which is secured to the flange 49a on the terminal 49 by means of the rivet 50. The terminal 49 is secured to the base 27 by screws 51 and carries the connecting screw 53, by which one of a pair of conductors (not shown) is connected to the terminal 49. The other conductor is connected by the screw 55 to the terminal 56, which is secured to the base 26 by the screws 57. The fixed end of the thermostatic element 59 is secured by the rivet 60 to the flange 61 on the terminal 56. The free end of the thermostatic element 59 carries the projection 62, which is engageable with the shoulder portion 70 on the latch cam 64. The latch cam is mounted for rotational movement on a spindle portion 65 of the insert 66 which is secured in the base 26. The pointed portion 69 of the latch cam engages the free end of the spring arm 46 to hold the movable contact 45 in engagement with the fixed or stationary contact 42. The flexible connector 63 is secured at or near the free end of the thermostatic element 59.

The embodiment of Figs. 9 to 12 differs from the embodiment of Figs. 1 to 8 in the omission of the projecting prongs and the employment of a connecting bridge 99. The bridge is generally in the form of a wide shallow U having a leg 100, to the inner surface and near the end of which the fixed contact 42 is secured, and a leg 101 to the outer side of which the flexible connector 63 is attached. The bridge has a base 102 provided with an opening 103, which receives a centering or locating projection 104 integrally formed on the base 26. The opening 103 and the projection 104 position the U-shaped bridge 99 so that the stationary contact 42 which is secured thereto is properly positioned for engagement with the movable contact 45 on the spring arm 46. The insulating pieces 52 and 53, which are clamped respectively between the base 26 and the terminal 49 and between the base 26 and the terminal 56, engage respectively the ends of the legs 101 and 100 of the bridge to hold the bridge against the base 26 and on the projection 104.

The embodiment of Figs. 9 to 12 is provided with a resetting member 105, which comprises an exterior button portion 106 which, in the disclosed structure, is circular and cylindrical, and has an interior shank 107 having a rectangular section and an actuating projection 108 which depends from the shank 107 and has a rectangular section. The interior shank 107 fits rather loosely between the region 77 of the cover 27 and a surface of the latch 64 so as to slide in a groove 107a in the region 77 of the cover 27, as depicted in Fig. 11. The actuating projection 108 is positioned for engagement with the protuberance 81 of the latch cam 64. The casing 20 is secured by screws 109a to a bracket 109, which is in turn secured by means such as rivets 110 to a panel 111. The panel has an opening 112 through which the button portion 106 of the resetting member 105 extends. The resetting member has straight-line movement because of the mounting of the portion 107 thereof in the

groove 107a, and so the actuating projection 108 can be moved in a straight line toward and away from the latch cam 64.

In operation of the panel mounting embodiment of our invention just described, one of the two conductors entering the casing 20 through the opening 96 and connected to the terminals 49 and 56 is connected to the electrical device to be protected, and the other of said conductors is connected to a source of electrical power. The other power connection to the device to be regulated is, of course, made directly. Current flows between the device to be regulated and the power source by way of one line conductor, the terminal 49, the spring arm 46, the contacts 45 and 42, the bridge 99, the connector 63, the thermostatic element 59, the terminal 56, and the other line conductor. When overload occurs, the thermostatic element 59 heats and flexes enough to move the projection 62 on the thermostatic element away from the shoulder portion 70 of the latch 64, and the spring arm 46 moves the movable contact 45 away from the stationary contact 42 and shifts the latch cam 64 about the spindle portion 65 until the curved surface 71 on the latch cam is opposite the projection 62. Separation of the contacts 42 and 45 breaks the circuit, and the thermostatic element then cools and returns to its original and normal position, with the projection 62 disposed for engagement with the latch cam 64. Before the device to be regulated can again be operated, the latch 64 must be reset. This is accomplished by shifting of the resetting member 105 linearly into the casing from the position shown in Figs. 9 and 10 so as to make the projection 108 on the resetting member engage the protuberance 81 and effect rotational movement of the latch cam. Incidentally, the position of the button portion 106 of the resetting member 105 may be employed to indicate the condition of the thermostatic device of Figs. 9 to 12. If the button portion is in, that is, protrudes only a small amount from the panel 111, then the latch cam 64 must be in the resetting position and the contacts 45 and 42 in engagement with one another. When overload has sufficiently heated the thermostatic element 59 to move it away from the latch cam 64, thereby permitting the latch cam to be angularly shifted to the position of Fig. 12 by the spring action of the spring arm 46, the latch cam will push the resetting member 105 so that the button portion thereof protrudes the maximum amount. Like the embodiment of Figs. 1 to 8, the embodiment of Figs. 9 to 12 has the thermostatic element 59 and the spring arm arranged in generally parallel side-by-side relation, the shoulder portion 70 and the pointed portion 69 of the latch cam 64 displaced from one another about 90 degrees, and the spindle portion 65 about which the latch cam 64 rotates generally aligned with the spring arm 46. The result of this arrangement is that the embodiment of Figs. 9 to 12 has the advantage of compactness that permits the embodiment to be arranged in an electrical fitting of about conventional width, such as illustrated by the casing 20.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we

claim as new and desire to secure by Letters Patent of the United States is:

1. A thermostatic switch comprising an insulating casing, a thermostatic element fixed in position at one end relative to the casing and extending in one direction from said one end and having a latching projection at the other end, a stationary contact supported in a fixed position relative to the casing, a movable contact, a resilient arm carrying the movable contact at one end thereof and at a position aligned for engagement with the stationary contact, means supporting the other end of the arm at a fixed position relative to the casing and so that the normal resilience of the arm tends to keep the movable contact out of engagement with the stationary contact, the arm extending generally in said one direction from one end to the other, and a latch element mounted for rotational movement relative to the casing and having a contact actuating portion engageable with the arm and a latch portion displaced angularly and linearly from the contact actuating portion, said latch portion of the latch element being releaseably engageable with the latching projection on the thermostatic element to hold the contact actuating portion against the arm so as to hold the movable contact in engagement with the stationary contact.

2. A thermostatic switch comprising an insulating casing, a thermostatic element fixed in position at one end relative to the casing and extending in one direction from said one end and having a latching projection at the other end, a stationary contact supported in a fixed position relative to the casing, a movable contact, a resilient arm carrying the movable contact at one end thereof and at a position aligned for engagement with the stationary contact, means supporting the other end of the arm at a fixed position relative to the casing and so that the normal resilience of the arm tends to keep the movable contact out of engagement with the stationary contact, the arm extending generally in said one direction from one end to the other, and a latch element mounted for rotational movement relative to the casing and having a contact actuating portion engageable with the arm and a latch portion displaced angularly and linearly from the contact actuating portion, said latch portion of the latch element being engageable with the projection on the thermostatic element to hold the contact actuating portion against the arm so as to hold the movable contact in engagement with the stationary contact, the arm being generally U-shaped and having a short leg carrying the movable contact and a long leg supported relative to the insulating casing by said means, and the said contact actuating and latch portions of the latch element being angularly displaced from one another approximately ninety degrees.

3. A plug connector type of thermostatic switch comprising an insulating casing, two spaced and generally parallel prongs mounted in the casing so as to extend generally in one direction from inner ends within the casing to outer ends outside of the casing, a thermostatic element having one end fixed to the casing and the other end free, said thermostatic element being provided with a projection and extending generally in said one direction from its fixed end to its free end, means electrically connecting the free end of the thermostatic element and one prong, a fixed contact secured to the other prong, a spring arm having one end fixed to the casing and the other end free, said spring arm being provided with a

movable contact engageable with the fixed contact and extending generally in said one direction from its fixed end to its free end in side-by-side relationship with the thermostatic element, the resilience of the spring arm being such that it normally biases the movable contact away from the fixed contact, and a latch element mounted for rotational movement on the casing and having angularly spaced portions engageable with the projection on the thermostatic element and the free end of the spring arm, whereby engagement of the projection on the thermostatic element with one of said portions of the latch element holds the latch element in a position such that the other portion thereof acts against the spring arm to hold the movable contact against the fixed contact, and when the thermostatic element heats sufficiently to shift the projection away from the latch element the latch element no longer holds the spring arm and the movable contact moves away from the fixed contact.

4. A plug connector type of thermostatic switch as specified in claim 3, and further comprising a reset member mounted for swinging movement relative to the casing and having a portion internal to the casing and engageable with the latch element, said reset member also having a portion external to the casing and exposed for manual manipulation, the reset member being swingable between a retracted position in which the external portion is transverse of the prongs and the internal portion is free of the latch and a projecting position in which the external portion extends between and generally in the direction of the external portions of the prongs and in which the internal portion effects movement of the latch element to a position such that the projection on the thermostatic element engages said one of the portions of the latch element to hold the movable contact in engagement with the fixed contact.

5. A plug connector type of thermostatic switch as specified in claim 4, and further comprising terminals securing the fixed ends of the bimetallic element and the spring arm to the casing adjacent the end thereof away from the end from which the prongs project, said casing having an opening therein adjacent the terminals for receiving conductors connectable with the terminals.

6. A plug connector type of thermostatic switch as specified in claim 3, and wherein the outer end of each prong is offset from the portion thereof which is inside of the casing, the interior portions being spaced farther apart than the exterior portions, and the thermostatic element and the spring arm being positioned between the interior portions of the prongs.

7. A plug connector type of thermostatic switch as specified in claim 3, and further comprising terminals securing the fixed ends of the thermostatic element and the spring arm to the casing adjacent the end thereof away from the end from which the prongs extend outside of the casing, said end of the casing adjacent the terminals having an opening therein for receiving conductors connectable with the terminals, and the combination further comprising insulating pieces clamped between the terminals and the casing and engaging the prongs to hold them in the casing.

8. A thermostatic switch comprising an insulating casing, a thermostatic element having a fixed end mounted on the casing and a free end, said thermostatic element extending in substantially a predetermined direction from its fixed

end to its free end and having a projection near its free end, a movable arm having a fixed end mounted on the casing and a free end provided with a movable contact and extending generally in the said predetermined direction in side-by-side relationship to the thermostatic element, and a bridge extending across the thermostatic element and the arm is spaced relation thereto, a fixed contact secured to one end of the bridge at a position for engagement with the movable contact, a connector providing an electrical connection between the other end of the bridge and the free end of the thermostatic element, and a latch element mounted for rotational movement on the casing and having angularly displaced portions engageable with the free end of the arm and the projection on the thermostatic element for holding the contacts in engagement.

9. A thermostatic switch as specified in claim 8, and wherein the bridge is generally in the form of a U, the stationary contact is secured to one leg of the U, the said connector is joined to the other leg of the U, and the said portions of the latch element are angularly displaced from one another approximately ninety degrees.

10. A thermostatic switch as specified in claim 9, wherein the latch element is located near one end of the casing, and the combination further comprises a manually movable resetting member projecting through said one end of the casing so as to be engageable with the latch element to effect movement of the same to a position in engagement with the arm and the projection on the thermostatic element, and terminals mounting the fixed ends of the thermostatic element and the arm near the other end of the casing, the said other end of the casing having an opening therein for receiving conductors connectable with the terminals.

11. A thermostatic switch as specified in claim 10, and further comprising insulating pieces clamped between the terminals and the casing and engaging the ends of the legs of the U-shaped bridge to hold it in place in the casing.

12. A thermostatic switch as specified in claim 11, and wherein the base of the U-shaped bridge has an opening therein, and the casing has a projection engaging the opening to locate the bridge properly in the casing.

13. A thermostatic switch comprising an insulating casing, a pair of prongs projecting from one end of the casing in fixed relationship to one another, a stationary contact mounted on one prong inside the casing, a movable contact shiftable toward and away from the stationary contact for engagement therewith, a thermostatic element electrically connected to the other prong inside the casing, means comprising a movable part interposed between the movable contact and the thermostatic element for effecting disengagement of the movable contact from the stationary contact in response to predetermined heating of the thermostatic element, and a resetting member mounted in the casing and movable to a resetting position in which it actuates said movable part in a manner to effect reengagement of the contacts, and in which position the resetting member projects from the said one end of the casing adjacent the prongs, the resetting member being of a size to prevent insertion of the prongs in an electrical fitting when it projects adjacent the prongs.

14. A thermostatic switch as specified in claim 13, and wherein the resetting member is mounted in the said one end of the casing for swinging

movement so as to move between the said resetting position in which it extends out from the said one end of the casing in the direction of projection of the prongs and an inoperative position in which it extends along the said one end of the casing and beyond the side thereof so as to be readily engageable for manual movement to the resetting position.

15. A thermostatic switch comprising an insulating casing comprising a base and a cover, a pair of prongs projecting from the casing, a stationary contact associated with one prong inside the casing, a movable contact positionable for engagement with the stationary contact, a thermostatic element mounted on the base, means enabling the thermostatic element when heated to take the movable contact away from the stationary contact, the base having an opening leading from its outer side to the thermostatic element and a recess in the outside of the base at the opening, and an adjusting element mounted in the opening so as to engage the thermostatic element, one edge of the cap having a tongue fitting in the recess in the base so as to cover the opening at the outside of the base.

16. A thermostatic switch comprising an insulating casing, a thermostatic element fixed in position at one end of the casing and extending freely along one side of the casing toward the other end thereof, said thermostatic element having a latching projection near its free end which extends away from said one side of the casing, a stationary contact supported in a fixed position relative to the casing on the side opposite the thermostatic element, a resilient arm carrying a movable contact near one end thereof at a position aligned for engagement with the stationary contact, the other end of said resilient arm being fixed in position relative to the casing at a position opposed to the fixed end of the thermostatic element, said resilient arm extending freely along the side of the casing opposite the thermostatic element and normally to biasing the movable contact away from the stationary contact, a latch element mounted in the casing between the resilient arm and thermostatic element, said latch element having a latch portion and a contact actuating portion separated thereon and disposed respectively for releaseable engagement with said latching projection on the thermostatic element and said resilient arm for retaining the contacts in engagement, and a manually operable member movably mounted on the casing for effecting movement of the latch element to its contact holding position.

17. A thermostatic switch as defined in claim 16, and further characterized by an adjustable element movable to adjusted positions relative to the casing and engaging the thermostatic element to effect adjustment of the temperature at which the latch portion of the latching element is disengaged by the latching projection of the thermostatic element.
